UNITED STATES PATENT OFFICE.

JOSEPH L. FIRM, OF BERWYN, ILLINOIS, ASSIGNOR TO THE GOSS PRINTING PRESS COMPANY, OF CHICAGO, ILLINOIS.

PRINTING-MACHINE.

No. 868,855.

Specification of Letters Patent.

Patented Oct. 22, 1907.

Application filed March 29, 1907. Serial No. 365,229.

To all whom it may concern:

Be it known that I, JOSEPH L. FIRM, a citizen of the United States, residing at Berwyn, in the county of Cook and State of Illinois, have invented certain new and useful Improvements in Printing-Machines, of which the following is a specification:

This invention relates to a machine for printing a web in colors and associating it with a plurality of other webs; then associating, cutting and folding the webs transversely; and then delivering them as one product.

In the present invention I use two sets of printing mechanisms arranged side by side, each consisting of a double printing couple having two form and four impression cylinders, in combination with a four color printing mechanism, consisting of five form and three impression cylinders, all in the same frame. The color mechanism is mounted upon the top of the main printing mechanisms, with the cylinders at right angles thereto, and the arrangement is such that space and room are provided to get at the color deck, which is very important for fast work.

The present invention includes the "cross-over" feature, whereby webs from one set may be crossed over and associated with the webs from the other set, and more particularly described and claimed in my pending application No. 358891.

Various forms of the invention are illustrated in the accompanying drawings.

30 Figure 1 is a diagrammatic side view of the printing mechanism with the color deck, and the color web being associated simply with the two webs printed by one set or side of the machine. Fig. 1^a is a similar view showing the webs crossed over from the right side to the left and associated with the color web. Fig. 2 is a plan view with the color deck removed. Fig. 3 is an end elevation showing the associating, folding, and delivery mechanism applied to the webs and delivered, as shown in Fig. 1^a, that is, with the two webs crossed over and associated with the two other plain webs and the color web. Fig. 4 is a similar end elevation of a modification. Fig. 5 is a diagrammatic side view of a modification by which, when no color is required, the web of the color deck can be printed plain and associated with the other webs. Fig. 6 is a diagrammatic end view of one set of the main printing couples.

It is to be understood that the black printing is done by the two main or lower printing mechanisms, and the colored web or supplement is printed on the top deck, the color press being mounted at right angles over the top of the main printing mechanisms, all the cylinders being four plates or pages wide.

Referring specifically to Figs. 1, 2 and 6 of the drawings, A indicates a roll at the side of the machine, the web from which passes over the rollers 1 and 2 to impression cylinder C where it is printed by form cylinder D, thence over the rollers 3 and 4 to impression cylinder E, and is printed upon its reverse side by form cylinder F, thence over the roller 5 and turning bar 6 and between the rollers 7 and 8, and over the roller 16 to the 55 rollers 20 and 21, where it meets the web B. This web B is fed from a roll at the end of the machine, and passes over roller 9 and turning bar 10, thence under roller 11 and over impression cylinder G, and is printed on its first side by form cylinder D, thence under the roller 65 12 to impression cylinder H and is printed upon its reverse side by form cylinder I, thence over roller 13, the turning bar 14 and roller 15, and thence under roller 17 to the rollers 20 and 21, where it meets the web A, as above described.

At the rollers 20 and 21, in the arrangement now under consideration, and illustrated especially in Fig. 1, the webs A and B meet the color web A². This passes from its roll at the opposite end of the press, through the color deck, the frame X of which is mounted upon 75 the main frame of the press below with a space of about two feet between, so as to allow a clear space for the manipulation of the various cylinders.

In printing the three primary colors I use the form cylinders L, M and O, and the key block or last color 80 on form cylinder P, the first side being printed on form cylinder J. These form cylinders are all handy to get at to put on the plates, and also to change the fountains, which are indicated at f, f', et seq., when a different color is required.

The color web A² passes from its roll over the rollers 24 and 25 to the impression cylinder I, and is printed on its first side by the form cylinder J; thence it passes between the rollers 26 and 27, and under roller 28, to impression cylinder K, and is printed upon its reverse 90 side by the form cylinder L, receiving its first color (yellow), and on the same impression cylinder receives its second color (blue) from the form cylinder M; thence it passes over the impression cylinder N, receiving its third color (red), from the form cylinder O, 95 and thence receives its fourth color from the key block on the form cylinder P, thence over and under the roller 29 where it is slit by the slitter 30, and thence it passes between the rollers 20 and 21 where it meets the webs A and B, which are slit by the slitter 19, 100 and the product then passes over the longitudinal folders 22 and 23, and to the delivery mechanism which will be hereinafter described, making four copies of twelve page papers with a colored supplement.

In the arrangement above described, the right side of the press, that is, the side printing the webs A' and B', may be idle, or it may be used to print and deliver sections from the right end of the press, in a manner similar to that already described with respect to the webs A and B, but of course without the colored supplement.

When no color is required from the top deck it may be modified as shown in Fig. 5, in which, by withdrawing 10 the gear 32 and using the gears 33 and 34, the cylinders N and P are changed in their rotation and the form cylinders M and O are silenced, the web A³ passing direct from its roll to the rollers 26 and 27 and thence over roller 28 to impression cylinder K where it is 15 printed on one side by form cylinder L and thence down under and around impression cylinder K and is printed upon its reverse side by form cylinder P, thence over rollers 35 and 36 and under roller 37 to rollers 20 and 21, where it meets the webs A and B, and 20 passes therewith down the formers 22 and 23, making twelve pages all in one color.

The webs A and B' may be crossed over from one set or side of the press to the other in the manner described more particularly in my pending application 25 No. 358891. When so crossed over they are associated as follows: the webs A and A' are associated and passed together around the roller 16, and to the upper set of longitudinal folders, and the webs B and B' are associated and passed together around the roller 17 to a 30 lower set of longitudinal folders and formers, as shown in Figs. 1^a and 3.

The longitudinal folders, or formers 22 and 23, and 22^a and 23^a, are placed above each other, as shown clearly in Figs. 3 and 4, and by doing this I am able 35 to lead the folded webs to the transverse cutting, folding and delivering carrier Q, placed at the right of said folders and at the side of the press and parallel thereto, and am able to associate all the longitudinal folded webs together as one product and stuff inside of each 40 other. These products may be of various denominations, such as eight, ten, twelve, fourteen or sixteen pages in sections.

The cutting, folding and delivery mechanism is substantially the same as shown and described in my 45 pending application No. 354101, with the difference that the cutting cylinders R and U are male cutting cylinders and hold the knives S and S' which co-act with the matrices V and V' on the carrier Q; also, the webs are all fed from one side of the machine as the 50 formers are above one another, and not side-by side as in said application, whereby floor space is saved.

Referring now to the delivery shown in Figs. 1^a and 3, the webs A and A', associated with the color web A³, pass between the rollers 20 and 21 and are slit by 55 the slitter 19, and are longitudinally folded by the formers 22 and 23, and the split halves pass respectively between the rollers 100 and 101, registering roller 200, and rollers 102 and 103 and are associated and passed between the rollers 104 and 105, where they meet the 60 webs B and B'. These webs, B and B', after passing over the roller 17, pass between the rollers 20' and 21' and are slit by the slitter 19', and thence down the formers 22^a and 23^a, which are located under the formers

22 and 23, and thence the split halves pass between the rollers 106 and 107, registering roller 201, and 65 rollers 108 and 109, thence between rollers 110 and 111, and thence upwardly between rollers 105 and 112, meeting the webs A, A' and A³, the webs all passing together to the carrier Q. On this carrier the webs are cut transversely by the knife S on the male cutting 70 cylinder R, co-acting with the matrix V on the carrier Q, and are pinned by the pins T, and having been cut and pinned are then thrust and transversely folded between the rollers 113 and 114 by the folding blade 122, the product then passing under tape 116 to the 75 rotary fly 117 and delivered to the apron 118. It will be seen that by this arrangement the sections are all stuffed and delivered together, thereby saving the time, labor and handling required in hand stuffing, and furthermore in this arrangement the colored supplement, passing over the formers 22 and 23, is placed 80 always on the outside of the paper. In this association just described the male cutting cylinder U, tapes 126 and delivery apron 202 are silenced and not used, since all the webs are associated and stuffed and delivered at only one side. When such stuffing is not desired the modification shown in Fig. 4 may be adopted. 85 In this the webs A, A' and A³ are led to the carrier Q from the formers 22 and 23 and are cut by the knife S, folded between the rollers 113 and 114 by the folding blade 102 and thence delivered to the apron 118. The webs B and B' are delivered from the formers 22^a and 23^a to the roller 205, passing thence over the roller 206 to the carrier Q, and are pinned by the pins T and cut by the knife S' co-acting with the matrix 90 V, and are thence thrust and folded between the rollers 123 and 124 by the folding blade 121, and pass then under the tapes 126 to the rotary fly 201, thence to the delivery apron 202, giving, in all, eight copies of eight page papers. 95

The colored supplement of two, four, six or eight pages can be added to any of the sections desired, and the different products possible are as follows; eight copies of eight pages, four copies of ten pages, four copies of twelve pages, four copies of fourteen pages, or four copies of sixteen pages, at each revolution. 105

I claim:

1. In a printing machine, the combination of a web perfecting cylinder printing mechanism having a longitudinal folder opposite the ends of the cylinders, and a supplemental web perfecting cylinder printing mechanism mounted above said mechanism, the cylinders of the respective mechanisms being at a right angle to each other, and means to associate the webs from the respective mechanisms and pass the same to the folder. 110

2. In a printing machine, the combination of a web perfecting cylinder printing mechanism, and a supplemental web perfecting cylinder printing mechanism mounted above said mechanism, the cylinders of the respective mechanisms being at an angle to each other, and means to associate, fold and deliver the webs from the respective mechanisms. 120

3. In a printing machine, the combination of a plural web perfecting cylinder printing mechanism, and a supplemental web perfecting cylinder printing mechanism mounted above said mechanism, the cylinders of the respective mechanisms being at a right angle to each other, and means to associate, fold and deliver the several webs. 125

4. In a printing machine, the combination of a plural web perfecting cylinder printing mechanism, upper and 130

lower longitudinal folders beside said mechanism, a carrier beside said folders, having transverse cutting, folding and delivering devices on opposite sides thereof, and means to optionally associate the webs from said folders and to pass the same to one side of the carrier or to pass disassociated webs to both sides of the said carrier.

5. In a printing machine, the combination of upper and lower longitudinal folders, means to optionally supply printed webs to one or both of said folders, a carrier 10 beside said folders having double sets of transverse cutting,

folding and delivery devices co-operating therewith, and means to optionally pass the webs from the said folders to one or both of said sets.

In testimony whereof I affix my signature, in presence of two witnesses.

JOSEPH L. FIRM.
